UNITED STATES PATENT OFFICE.

DOMINICK A. REAGAN, OF ALTOONA, PENNSYLVANIA, ASSIGNOR OF ONE-THIRD TO FREDERICK HESSER, OF ALTOONA, PENNSYLVANIA.

SAFETY DEVICE FOR STEAM-BOILERS.

SPECIFICATION forming part of Letters Patent No. 738,844, dated September 15, 1903.

Application filed January 17, 1903. Serial No. 139,468. (No model.)

To all whom it may concern:

Be it known that I, DOMINICK A. REAGAN, a citizen of the United States, residing at Altoona, in the county of Blair and State of Pennsylvania, have invented certain new and useful Improvements in Safety Devices for Steam-Boilers; and I do hereby declare the following to be a full, clear, and exact description of the invention, such as will enable others skilled in the art to which it appertains to make and use the same.

This invention relates to safety devices for preventing explosions of steam-boilers, and has for its object to provide a new and improved device by means of which, if the water should get too low in a steam-boiler, an opening will be automatically made in the partition or wall between the water and steam space and the combustion-chamber or fire-box of a boiler and steam and water admitted thereto to extinguish the fire.

In carrying out the invention the wall or partition in a steam-boiler at any suitable point or position between the water and steam space and the combustion-chamber or fire-box is provided with an opening and a hollow projection or cap fastened over said opening and projecting into the water or into the fire-space, said cap being of such thickness and construction as to withstand the pressure in the boiler and when the water has fallen away from the cap to burn and become loosened, thus causing a leak and admitting steam and water to the fire-box or combustion-chamber to extinguish the fire.

Referring to the accompanying drawings, in which similar figures of reference indicate like parts, Figure 1 is a view of a portion of a locomotive-boiler, showing the invention applied thereto. Fig. 2 is a detail view showing the manner of attaching the cap to the boiler. Fig. 3 is a view showing another way of attaching the cap to the boiler. Fig. 4 is a view showing a modification in the construction of the cap. Fig. 5 is another modification of the cap, showing it plain.

While the invention may be applied at any suitable part of a steam-boiler of different makes between the steam and water space and the combustion-chamber or fire-box, to illustrate one way of carrying out the inven-

tion I have shown it as applied to the crown-sheet 1 of a steam-boiler, 2 being the fire-box.

Referring to Fig. 2, a suitable opening 3 is formed in the crown-sheet 1, and a hollow projection or cap 4, of preferably the same metal as the crown-sheet and projecting into the water and steam space 5, is fastened over the opening 3. One way of attaching the cap 4 is as follows: The hole or opening 3 is formed with a flange 6, projecting into the water and steam space 5, said flange being formed with an offset 7, close to the crown-sheet. The cap 4 is fastened over the opening 3 by roiling or expanding it, with a flange 8 setting into the offset 7, the operation being similar to roiling or expanding a tube or flue into a tube-sheet. The cap 4 is preferably of the same material as the crown-sheet, but is somewhat thinner. The cap 4 is preferably corrugated, and as herein shown is vertically corrugated, thereby strengthening the cap to resist the pressure for the purpose hereinafter set forth, and is preferably corrugated, as at 9, to assist in withstanding the steam-pressure. In the event of the water in the boiler falling below the upper part of the cap 4, as indicated, the cap will become highly heated, owing to the intensity of the heat in the fire-box or combustion-chamber, and burn out, break, burst, or collapse, and may also become loosened from its fastening and allow the steam and water to pass down into the fire-box and extinguish the fire. Another way of attaching the cap to the crown-sheet is shown in Fig. 3, where a tubular nut 10 is employed, which is screwed into the opening 3 in the crown-sheet, forming a steam or water tight joint, and the cap 4 is secured to the nut 10 by roiling or expanding, the flange 8 of the cap setting into an offset 11 in the nut.

In lieu of the cap 4 being vertically corrugated, as in Fig. 3, it may be horizontally corrugated, as shown by cap 4' in Fig. 4.

In Fig. 5 I have shown a modification where the cap is plain, as the cap 4"; but the corrugated form is preferable.

In this invention as herein presented there is a cap covering an opening in the crown-sheet or other suitable partition of a steam-boiler of such a thickness as to resist the steam-pressure, but when the water may be-

come too low will burn and loosen from its fastening, permitting a leak of steam and water to the fire-box to put out the fire.

I am aware that fusible plugs in connection with steam-boilers to obtain a leak and put out the fire are old, and such are not analogous to this invention.

Having thus described my invention, what I desire to secure and claim by Letters Patent is—

1. A steam-boiler having an opening in the partition between the water and steam space, and the combustion-chamber, or fire-box, and a cap secured to said partition, oversaid opening, said cap being of such thickness, as to withstand steam-pressure, but adapted to burn away and become loose from its fastening, when the water in the boiler falls below the cap, as herein set forth.

2. A steam-boiler, having an opening in the partition between the steam and water space, and combustion-chamber, and a cap secured over said opening, the cap being of thin material, which will burn, and separate from its fastening when the water in the boiler becomes low, said cap being corrugated, as herein set forth.

3. A steam-boiler having an opening in the partition between the steam-space and combustion-chamber, and a tubular nut secured in said opening, in combination with a cap secured to said nut, said cap being of metal

of such thickness as to withstand the steam-pressure in the boiler, but which will burn, and loosen from its fastening when the water 35 in the boiler becomes low, as herein set forth.

4. A steam-boiler, having an opening in the crown-sheet, formed with a flange projecting outside of the crown-sheet, and having an offset, in combination with a cap having a flange 40 set into said offset; the cap projecting into the boiler, and being of thin metal, which will withstand steam-pressure, but will burn, and become loose from its joint, when the water in the boiler becomes low, as herein set forth. 45

5. In a steam-boiler, a partition between the water and steam space and the combustion-chamber, having an opening, and a cap secured over said opening, said cap being of thinner metal than the crown-sheet, and projecting into the steam-space, and secured to a support about said opening, whereby when the water in the boiler becomes low, and removed from the cap, the latter will burn, and become detached from its fastening, and steam 55 and water admitted to the fire-box, as herein set forth.

In testimony whereof I affix my signature in presence of two witnesses.

DOMINICK A. REAGAN.
